UNITED STATES PATENT OFFICE.

JOHN P. LINDSAY, OF WEST DERBY, VERMONT.

GARMENT-SUPPORTER.

SPECIFICATION forming part of Letters Patent No. 392,042, dated October 30, 1888.

Application filed May 10, 1888. Serial No. 273,395. (No model.)

To all whom it may concern:

Be it known that I, JOHN P. LINDSAY, a citizen of the United States, residing at West Derby, in the county of Orleans and State of Vermont, have invented a new and useful Improvement in Garment-Supporters, of which the following is a specification.

The invention relates to improvements in garment-supporters in which the fabric is clamped around a stud.

Heretofore garment-supporters have been constructed with a portion having a headed stud adapted to receive the fabric, which is secured by passing the stud and the fabric through an enlarged opening in another portion of the clasp, then down into a smaller opening, where they are retained. This manner of securing the fabric is objectionable, inasmuch as it requires many motions to adjust it, and when adjusted there is always a liability of its slipping, the fabric being clamped only on the under side of the stud.

The object of this invention is to obviate these objections and provide a clasp of simple and uncomplicated construction, in which the operation of clamping is performed by direct action of the clamping portion, insuring quickness and convenience, and in which the fabric is clamped on all sides of the stud by a broad bearing-surface, which securely holds and prevents it becoming injured or torn; and, furthermore, the object of the invention is to provide a clasp for garment-supporters that will adapt itself perfectly to the various thicknesses of fabrics.

The invention consists in the novel combination and arrangement of the parts herein-after fully described, illustrated in the accompanying drawings, and pointed out in the claims hereto appended.

In the accompanying drawings, forming part of this specification, and in which like letters of reference designate corresponding parts, Figure 1 is a perspective of a clasp constructed in accordance with this invention, illustrating the device preparatory to clamping a garment, the swinging and clamping jaws resting on the head of the stud. Fig. 2 is a detail perspective view of one of the jaws, showing the tapering stud and the spring that is preferably formed integral with the jaw. Fig. 3 is a vertical longitudinal sectional view of the clasp

illustrated in Fig. 1, showing the tapering stud on one of the jaws and the eye or opening having the outward-turned edges of the other jaw. 55

Referring to the accompanying drawings, A designates a clasp constructed of suitable material, preferably of sheet metal, and consisting of a fixed jaw, A', provided with a stud, a, and a swinging and clamping jaw, 60 A², having an eye or opening, a', formed in it, the two jaws A' and A² being hinged together at their upper ends by a pintle, whereby, when the fabric is placed on the stud between the same and the clamping-jaw, it will be clamped 65 upon all sides by the direct downward action of the swinging clamping-jaw A². The stud a is constructed tapering, the smallest portion being at the end where it meets the eye or opening a' of the swinging and clamping jaw 70 A², and the edge of the eye or opening is turned outward and is flaring, and the eye or opening a' is largest at the point where it meets the stud a. By this construction the clasp will perfectly adapt itself to the variations in thickness of the fabrics to be clamped. The thinner 75 the fabric, the farther down on the stud the swinging and clamping jaw will slip to hold said fabric, and the fabric will be securely held without liability of becoming injured from sharp edges or curvatures, it being clamped 80 around the stud upon all sides and especially at the top, where the most secure hold can be obtained by a broad bearing-surface.

The fixed jaw A', which is constructed of 85 sheet metal, has formed in it or attached to it a spring, a², against which bears a heel, a³, formed in the upper portion of the swinging and clamping jaw A². The heel a³ contacts with the spring a² when the swinging and 90 clamping jaw A² is raised from the stud a, and is forced by the spring in the direction of the stud a. When the swinging and clamping jaw reaches the head of the stud a, the heel a³ is raised from the spring a², whereby the swinging and clamping jaw is caused to remain inactive at the end of the stud without exerting 95 spring-pressure on the stud.

The device is secured to the webbing or band B of the garment-supporter by turning the 100 lower end of the fixed jaw A' over the webbing or band B and by passing the webbing or band B through slots a⁴ at the top of the fixed jaw. By securing the device in this manner and

passing the band or webbing up the back the metal is prevented coming in contact with the flesh, and the necessity of sewing or riveting the device to the band or webbing is dispensed with.

From the foregoing description and the accompanying drawings the construction, operation, and advantages of the invention will readily be understood, and it will clearly be seen that clasps constructed in accordance with this invention are of cheap and uncomplicated construction; that they will firmly clasp the fabric upon all sides of the stud by the direct action of the clamping-jaw, and that they will securely retain the fabric when clamped without liability of injuring it, and will also readily adapt themselves to the varying thickness of fabrics.

Having described my invention, I claim—

1. A clasp for garment-supporters, consisting of two jaws hinged together, one provided with a stud and a spring and the other having an eye or opening and a heel located above and out of contact with the spring, said heel being adapted to engage the spring when the jaw leaves the head of the stud, whereby the jaw is forced in the direction of the stud, but

allowed to rest thereon without the exertion of spring-pressure, substantially as and for the purpose described.

30

2. A clasp for garment-supporters, consisting of a fixed jaw provided with a tapering stud and a swinging and clamping jaw hinged to the fixed jaw and having an eye or opening formed in it with outward-turned edges to 35 form a broad bearing-surface, whereby the clasp will readily adapt itself to the various thicknesses of fabrics, substantially as described.

3. A clasp for garment-supporters, consisting of a fixed jaw provided with a tapering stud, a swinging and clamping jaw hinged to the fixed jaw and having an eye or opening with outward-turned edges to form a broad bearing-surface, and a spring integral with 45 one of the jaws, substantially as and for the purpose described.

In testimony that I claim the foregoing as my own I have hereto affixed my signature in presence of two witnesses.

JOHN P. LINDSAY.
